UNITED STATES PATENT OFFICE.

RICHARD A. HILL, OF WASHINGTON, DISTRICT OF COLUMBIA.

IMPROVEMENT IN FIRE-PLUGS.

Specification forming part of Letters Patent No. **90,540**, dated May 25, 1869.

To all whom it may concern:

Be it known that I, RICHARD A. HILL, of Washington, in the county of Washington and District of Columbia, have invented a new and valuable Improvement in Fire-Plugs; and I do hereby declare that the following is a full, clear, and exact description of the construction and operation of the same, reference being had to the annexed drawings, making a part of this specification, and to the letters and figures of reference marked thereon.

Figure 1 of the drawings is a representation of an external front view of my device. Fig. 2 is a top view of the same with the cover removed. Fig. 3 is a vertical section thereof.

My invention relates to fire-plugs.

The letter A of the drawings represents a box set in the sidewalk, and having a water-conductor to the bottom thereof, marked B on the drawings. The letter C is a strainer, adjusted as shown, through which the water passes upward to the fire-plug. The letter D is a man-hole. The letter E is a box adjusted on the top of box A, in which I place a series of pipes, marked F, with outlets G. The letter a is the valve-stem, constructed hollow, as shown, and having a valve, e, attached thereto. The letter c is a screw-nut, working on threads on the outer side of the valve-stem, as shown, and having threads on its outside adapted to threads on the inner side of the pipe F. This screw-nut c, when raised, admits the water to the pipe through the hollow valve-stem, and when lowered not only closes the opening to said valve-stem, but also opens or uncovers a small aperture through said stem, marked i,

through which the water remaining in the pipe may pass outward through a similar opening in the pipe itself. The letter s is a rod attached to the valve-stem, arranged for operating by turning the wheels v. The letter y is an outlet for the waste water from the pipes, and the letters u are the threads and openings to which the hose is attached. The letter P is a cover for the box E.

It will readily be discovered that the pipes herein described may be removed with great ease, and that several fire-engines may be accommodated with water at the same time; also, that freezing of water in the pipe or valve is rendered almost impossible.

What I claim as my invention, and desire to secure by Letters Patent, is—

1. The screw-nut c, in combination with the hollow valve-stem a and the waste-water openings, as described, substantially as and for the purposes set forth.
2. The case E, surmounted by a cap, and containing a plurality of plugs, as above described, and constituting a common receptacle for the leakage, all substantially as described.
3. The combination of the parts A and E of the case with an intermediate plate, in which a plurality of plugs is seated, substantially as described.

In testimony that I claim the above I have hereunto subscribed my name in the presence of two witnesses.

RICHARD A. HILL.
